UNITED STATES PATENT OFFICE.

ALFRED HEYDRICH, OF NEW YORK, N. Y.

FLOWER-HOLDER.

SPECIFICATION forming part of Letters Patent No. 642,328, dated January 30, 1900.

Application filed April 22, 1899. Serial No. 714,012. (No model.)

To all whom it may concern:

Be it known that I, ALFRED HEYDRICH, a subject of the German Emperor, residing in the city of New York, borough of Brooklyn, 5 county of Kings, and State of New York, have invented certain new and useful Improvements in Flower-Holders, of which the following is a full, clear, and exact description.

My invention relates to what I term a 10 "flower-holder;" and the main object of said invention is to provide a simple and efficient holder which is provided with means for supporting the flowers in place in the form of a bouquet and in which a containing-receptacle 15 normally hidden from view is provided.

To these ends my invention consists in a flower-holder of the character to be hereinafter described and claimed, reference being had to the accompanying drawing, in which 20 the single view presented is a central longitudinal sectional view of one form of device embodying my invention, the flowers being shown in position thereon.

In the drawing, A represents a suitable 25 base, which is preferably made of cardboard or some such suitable material. In the present instance I have shown depending from this base A a hollow handle a, which may likewise be made of cardboard. To the lower 30 end of this handle is secured in any suitable manner an abutment b, which may be in the nature of an ornamental plug, which closes the lower end of the hollow handle and constitutes a bearing for one end of an expansible spring c. This spring c is contained 35 within the hollow portion d of the depending stem e, projecting from a movable carrier B, the upper end of the spring bearing against the full portion of the stem, as indicated at 40 f, so as to tend to project the carrier B outwardly. The stem e carries a suitable spring- 45 catch g, which is adapted to engage in an aperture h and maintain the carrier in the retracted position against the tension of the spring c, as indicated in full lines in the drawing. The carrier B may be of any suitable form or construction and is adapted to be received within a containing-receptacle C in the body of the holder. It is essential, 50 however, that the containing-receptacle be normally closed or hidden from view, and the carrier in the present instance is made to an-

swer a twofold purpose, as will hereinafter appear. Thus the base i of the carrier may be made of sufficient dimensions to support 55 various articles, such as articles of jewelry intended as presents, and the base will at the same time afford a support for standards j, which are united by a cap-piece k. This cap-piece k constitutes a cover for the containing- 60 receptacle and is preferably provided with a foraminous support l, into which the stems of flowers m may be secured. This foraminous support l is in line with a like main flower-support D, extending from the base A 65 to the support l when the carrier is in the retracted position. Flowers n may be held in place upon the support D, and when the carrier B is in the retracted position the containing-receptacle will be covered with flowers, 70 and the device has the appearance of an ordinary bouquet. If desired, a perch o may be suspended from the cap-piece k, and an artificial bird or like object may be sustained upon the perch. 75

When the spring-catch g is depressed, the carrier B, together with the cover k and the flowers supported thereby, will be suddenly projected from the containing-receptacle to the position indicated in dotted lines, when 80 the bird will be brought into view and the article supported upon the base i or within the containing-receptacle will be exposed. The element of surprise enters into the device, and a pleasing effect is produced by the sudden appearance of the bird in a bower covered and surrounded with flowers. 85

It is obvious that various changes in construction and detail may be made without departing from the spirit of my invention. For 90 instance, the carrier may be pulled out or moved to the dotted-line position by hand instead of being forced to such position by means of a spring.

Having described my invention, what I 95 claim, and desire to secure by Letters Patent, is—

1. In a flower-holder, the combination of a base, a handle connected thereto, a main flower-support mounted upon said base, a containing-receptacle beneath said support and a removable cover for said receptacle. 100

2. In a flower-holder, the combination of a main flower-support, a containing-receptacle

beneath said support, a removable cover for said receptacle and a movable carrier adapted to be contained within said containing-receptacle.

5. 3. In a flower-holder, the combination of a main flower-support, a containing-receptacle beneath said support, a removable cover and a movable spring-pressed carrier adapted to be contained within said containing-receptacle and to be ejected therefrom.

4. In a flower-holder, the combination of a main flower-support, a containing-receptacle beneath said support, a movable spring-pressed carrier adapted to be contained within said receptacle and to be ejected therefrom, and a cover for said receptacle supported by said carrier.

5. In a flower-holder, the combination of a main flower-support, a spring-pressed carrier adapted to be received beneath said support and to be projected above the same by the spring thereof and means for retaining the carrier in its retracted position and for releasing it so that it may be projected from beneath the support.

6. In a flower-holder, the combination of a main flower-support, a spring-pressed carrier adapted to be received beneath said support and to be projected above the same by the spring thereof, a cover supported upon said carrier and adapted to cover the carrier from observation when the carrier is retracted and means for retaining the carrier in its retracted position and for releasing it, so that it may be projected from beneath the support.

35. 7. In a flower-holder, the combination of a main flower-support, a spring-pressed carrier

adapted to be received beneath said support and to be projected above the same by the spring thereof, a cover supported upon said carrier and adapted to cover the carrier from observation when the carrier is retracted, means for supporting flowers upon said cover so that when the carrier is retracted and flowers are in place, the device will have the appearance of an ordinary bouquet and means for retaining the carrier in its retracted position and for releasing it so that it may be projected from beneath the support.

8. In a flower-holder, the combination of a base, a handle connected thereto, a main flower-support mounted upon said base, a containing-receptacle between said base and flower-support, a spring-pressed cover adapted to cover said receptacle and to form a continuation of the main flower-support when the cover is in place and means for supporting flowers upon said cover.

9. In a flower-holder, the combination of a base, a handle depending therefrom, a main flower-support mounted upon said base, a containing-receptacle between the base and the flower-support, a spring-pressed cover adapted to cover said receptacle and to form a continuation of the main flower-support when the cover is in place, means for supporting the flowers upon said cover and a figure supported by said cover and exposed to view when the cover is projected outwardly to uncover the receptacle.

ALFRED HEYDRICH.
